PORTABLE STARTING PLATFORM FOR SWIMMERS

Quentin D. De Muth, Box 157B, Rte. 1, Buckeye, Ariz.,
and William E. Greene, 711 W. Windsor Ave., Phoenix, Ariz.

Filed Aug. 31, 1961, Ser. No. 66,558

Term of patent 14 years

(Cl. D34—5)

FIG.-1

Des. 194,399

PAGE 2

FIG.-5

FIG. 1 is a perspective view of a portable starting platform for swimmers showing our new design;

FIG. 2 is a perspective view showing sides opposite those shown in FIG. 1;

FIG. 3 is a top plan view;

FIG. 4 is a front elevational view; and

FIG. 5 is a side elevational view.

The essential features of the design reside in the portions shown in full lines on the drawing, and consisting of a decorative notch and tapering sides and risers, all as shown.

We claim:

The ornamental design for a portable starting platform for swimmers as shown and described.
